UNITED STATES PATENT OFFICE.

JOSEF DORNBUSCH, OF CREFELD, GERMANY.

DESIGN FOR WALL PAPER OR SIMILAR ARTICLE.

Application filed March 13, 1926. Serial No. 16,908. Term of patent 7 years.

To all whom it may concern:

Be it known that I, JOSEF DORNBUSCH, a citizen of Germany, residing in the city of Crefeld, in the Republic of Germany, have invented a new, original, and ornamental Design for Wall Paper or Similar Articles, of which the following is a specification, reference being had to the accompanying drawing, forming part thereof, which illustrates a plan view of a piece of wall paper or similar article embossed with my new design.

I claim:

The ornamental design for wall paper or similar article, as shown.

JOSEF DORNBUSCH.
